OIL HEATER

Filed March 19, 1923 2 Sheets-Sheet 2

FIG. 3.

Inventor
John Primrose
By his Attorneys
Cooper, Kerr & Dunham

UNITED STATES PATENT OFFICE.

JOHN PRIMROSE, OF DONGAN HILLS, NEW YORK, ASSIGNOR TO POWER SPECIALTY COMPANY, OF NEW YORK, N. Y., A CORPORATION OF NEW YORK.

OIL HEATER.

Application filed March 19, 1923. Serial No. 626,239.

To all whom it may concern:

Be it known that I, JOHN PRIMROSE, a citizen of the United States of America, residing at Dongan Hills, in the county of 5 Richmond and State of New York, have invented certain new and useful Improvements in Oil Heaters, of which the following is a full, clear, and exact description.

This invention relates to improvements 10 in oil heaters and is particularly directed to a construction of heater which is capable of handling large quantities of oil and raising the temperature thereof to the desired amount.

15 Provision is made for absorbing the maximum amount of heat from the hot gases without, however, overheating the oil at any point in the heater.

To this general end I have devised a novel 20 disposition of the heating surfaces in the heater and have protected such portions as are subject to excessive radiant heat by tile. I have further provided a novel circulating path for the oil through the heater so that 25 the maximum amount of heat is absorbed.

In the drawings,

Fig. 1 is a sectional view of my improved heater.

Fig. 2 is a detail view showing one tube 30 and its encircling protecting tile.

Fig. 3 is a front view of the heater and shows the distributing manifold or header construction.

The furnace walls are of ordinary construction and a bridge wall 10 is built up 35 to divide the furnace into two chambers 11 and 12. The source of heat is applied within the furnace chamber and may be a coal fire or gas or fuel oil flame. From the furnace chamber the hot gases pass over the bridge through the heating chamber 12 and thence out of the apparatus through a duct 13.

The oil-conveying parts of the heater 45 comprise a central outlet manifold 14 connected to a central vertically extending header 15. This header receives oil through laterally extending pipes 16 which in turn are connected at their outer ends into vertical or end headers 17. The tubes 16 extend substantially over the entire front wall of the furnace and are protected against the effect of high radiant heat by encircling tile 18, as shown in Fig. 2. U-shaped conduits 50 19 connect each of the headers with a trans-

verse horizontal header 20 into which roof tubes 24 are fitted. The tubes 24 extend across the roof of the furnace and connect through individual junction boxes 22 with vertical tile covered tubes 22^a which are located in the rear wall of the furnace. The portions of the tubes 24 which are directly exposed to the heat of the furnace chamber are preferably protected by encircling brick tile, such as 18, and the remaining portions of the tubes are preferably encased in blocks 23 of cast iron. The pipes 22^a convey the oil to the junction boxes from the bank of heating tubes 25 which receive oil from inlet header 26. The tube bank 70 25 is preferably formed of a plurality of superimposed tubes, each having corrugated cast iron casings thereon and having the usual connecting headers or couplings at their ends. This bank of heating elements 75 25 receives heat by convection from the passing hot gases and the upper tubes of the bank are protected against burning out by excessive radiant heat from the roof by the provision of the opposed heating surface 80 in the roof. This feature of the apparatus per se is not herein claimed as it forms the subject matter of my copending application Serial Number 482,135.

It will be observed that all portions of 85 the tubes 16 and 24 which are directly exposed to the flames in the furnace chamber, and the highly heated radiant walls of the bridge wall are protected by encircling 90 brick tile 18. This tile prevents the oil in these tubes from being overheated and also prevents so-called hot spots from forming on the tubes themselves. The tile and tubes together form the entire front wall and roof of the furnace.

The oil in passing through the pipes in the roof and front wall of the furnace cool 95 these parts of the apparatus and prevent overheating thereof. At the same time heat which otherwise would be dissipated outside 100 the furnace is usefully recovered by the oil.

In certain cases it may be desirable to reverse the direction of flow of the oil through the apparatus. The oil would then be supplied at 14 and drawn off at header 105 26.

The hollow bridge wall is provided with an opening 27 through which the inner headers of the tube bank 25 project. This construction permits ready access to the in- 110

ner headers for inspection or replacement. Furthermore the removal of one or more tubes is facilitated since any desired inner headers can be removed from inside the bridge wall and thereafter the desired tubes can be displaced bodily to the right in Fig. 1.

By making the bridge wall hollow instead of solid, the overheating of that portion of the wall adjacent the tube bank 25 is prevented. With solid bridge walls it has been found that under very high temperature conditions in the furnace chamber that the entire wall may possibly become radiant and thus overheat the oil in tubes 25. By allowing air to have access to the interior of the bridge wall, this objectionable overheating is obviated.

What I claim is:

- 20 1. An oil heater comprising in combination with a central vertical header, of a bank of oil conveying pipes extending laterally from said header, a pair of vertical headers at the ends of said pipes, a horizontal header with a bank of tubes connected thereto, disposed above said first mentioned bank of pipes, connections from said horizontal header to the aforesaid pair of vertical headers, a bank of tubes disposed in the path of heated gases and connections from said bank of tubes to the bank of tubes which are connected to the horizontal header.
- 25 2. An oil heater comprising a furnace chamber with a bridge wall therein to divide the same into a furnace and a tube chamber, a bank of tubes having encircling tile thereon forming the front wall of the furnace chamber, a second bank of tubes having encircling tile and cast iron blocks thereon to form the roof of the furnace, a third bank of tubes in the tube chamber disposed in the path of hot gases flowing therethrough, and means connecting the first and second banks of tubes.
- 30 3. An oil heater comprising a furnace chamber, a front wall therefor, comprised of a divided bank of tubes, a header disposed intermediate said tubes and connected thereto, a second bank of tubes forming the roof of the furnace chamber, a header therefor connected to said tubes which form the front wall of the furnace chamber, and a third bank of tubes disposed in the path of

hot gases to which the aforesaid second bank of tubes are connected.

4. An oil heater comprising a plurality of horizontally extending vertically superimposed tubes adapted to form one wall of a furnace chamber, a second bank of horizontally extending tubes disposed side by side forming the roof of the furnace chamber, a third bank of tubes disposed in the path of hot gases, and encircling tile for all the tubes of the first mentioned wall and for a portion of the roof tubes to protect the same and the oil therein from the direct effects of radiant heat.

5. An oil heater comprising a chamber, a hollow bridge wall therein to divide the same into a furnace chamber and a tube chamber, a bank of heat absorbing tubes disposed in the tube chamber, said tubes having header connections at one end projecting through an opening in the hollow bridge wall so as to be accessible from the interior of said hollow bridge wall.

6. An oil heater comprising a chamber, a bridge wall therein to divide the same into a furnace chamber and a tube chamber, a bank of oil conveying tubes in said tube chamber, said bridge wall being hollow to prevent parts of the same adjacent the tube chamber from becoming overheated.

7. An oil heater comprising a furnace chamber and a tube chamber, a bank of tubes having encircling tile thereon and defining one wall of the furnace chamber, a second bank of tubes disposed at the roof of both chambers, said tubes being in part encased by encircling tile, a third bank of tubes in the heating chamber disposed in the path of hot gases flowing therethrough, and means connecting the first and second and the second and third banks of tubes.

8. An oil heater comprising a plurality of horizontally extending vertically superimposed tubes disposed to define one wall of a furnace chamber, a second bank of horizontally extending tubes disposed side by side and defining the roof of the furnace chamber, a third bank of tubes disposed in the path of the hot gases and cast iron casings upon a portion of said roof tubes and said tubes in the path of the hot gases for the purpose described.

In testimony whereof I hereto affix my signature.

JOHN PRIMROSE.
